UNITED STATES PATENT OFFICE

115,700

DESIGN FOR A BELT

Frederick M. Blossom, Peoria, Ill.

Application September 2, 1938, Serial No. 79,681

Term of patent 3½ years

To all whom it may concern:

Be it known that I, Frederick M. Blossom, a citizen of the United States, residing at Peoria, in the county of Peoria and State of Illinois, have invented a new, original, and ornamental Design for a Belt, of which the following is a specification, reference being had to the accompanying drawing, forming part thereof.

Fig. 1 is a perspective view of a belt showing my design.

Fig. 2 is an enlarged fragmentary elevation of the front thereof.

Fig. 3 is a transverse sectional elevation of the buckle portion shown in Fig. 2.

Fig. 4 is a plan view of the fragmentary portion shown in Fig. 2.

The characteristic features of my design reside in the portions shown in solid black lines on the drawing.

I claim:

The ornamental design for a belt, as shown and described.

FREDERICK M. BLOSSOM.
